MEANS FOR SUSPENDING CURTAINS AND SIMILAR DRAPERIES

Filed May 14, 1924

UNITED STATES PATENT OFFICE

REUBEN BIGLAND, OF HANDSWORTH, ENGLAND, ASSIGNOR OF ONE-HALF TO
FREDERICK WILLIAM JONES, OF NEWARK, NEW JERSEY

MEANS FOR SUSPENDING CURTAINS AND SIMILAR DRAPERIES

Application filed May 14, 1924, Serial No. 713,240, and in Great Britain September, 1923.

This invention relates, generally, to improvements in means for suspending curtains, portières, and similar hangings or draperies.

The invention has for its principal object to provide a novel construction of combined supporting rail and traveling suspension means for suspending curtains and similar draperies, so that the same may be adjusted or moved with a minimum of effort, and without danger of tearing or injuring the most delicate drapery material, while at the same time a neat and pleasing effect is obtained. To this end the invention consists in providing a novel supporting track in connection with which are arranged a plurality of traveling suspension devices, which, by reason of their novel ball-bearing construction, are substantially frictionless, and consequently are readily and quickly responsive to the lightest pull upon the curtain or other drapery, when adjusting the latter.

Other objects of this invention, not at this time more particularly enumerated, will be clearly understood from the following detailed description of the same.

With the various objects of this invention in view, the same consists, primarily, in the novel construction of suspension means for curtains and similar draperies hereinafter set forth; and the invention consists, furthermore, in the several novel arrangements and combinations of the various devices and parts, as well as in the details of the construction thereof, all of which will be hereinafter more fully described, and then finally embodied in the claim which is appended hereto.

The invention is clearly illustrated in the accompanying drawings, in which:

Fig. 1 is a face view or front elevation of the novel means for suspending curtains or similar draperies, made according to and embodying the principles of this invention; Fig. 2 is a plan or top view of the same; Fig. 3 is a fragmentary view showing a modified arrangement of bracket for supporting the track or rail; and Fig. 4 is a fragmentary vertical cross section, drawn on an enlarged scale.

Similar characters of reference are employed in all of the hereinabove described views, to indicate corresponding parts.

Referring now to said drawings, the reference character 5 indicates the novel supporting rail in connection with which the novel traveling suspension devices are arranged. Said rail 5 possesses a central vertical web or flange 6, from the lower end of which spring oppositely directed horizontal track flanges 7, provided on their upper surfaces with concave track channels 8. The supporting rail thus formed is of substantially inverted T-shape, and is consequently strong and durable, and yet can be bent to follow any shape of window if it is so desired.

The ends of a given rail section or length are preferably bent or curved to project substantially at right angles to the main body thereof, as indicated at *x* and *y* in Fig. 2.

The means for hanging or supporting the novel rail in connection with a window or door frame or embrasure, comprises, in one form, an over-head bracket or hanger consisting of a horizontal foot-piece 9 from one end of which extends a downwardly directed or vertical hanger arm 10. Said foot-piece 9 is arranged against the underside of the lintel 11 of a window or door frame, and may be secured thereto by fastening screws 12 so that the hanger arm 10 depends therefrom. Said brackets or hangers are employed in pairs, one adjacent to each stile or side of the window or door frame, and the rail is supported by and between the free ends of the hanger arms 10 thereof. The means for attaching the rail ends to the respective hanger arms 10, comprise bolts 13, which are respectively passed through the vertical web or flange 6 at each turned end *x* and *y* of the rail, the free end of each bolt 13 passing through the end of a hanger arm 10. A spacing sleeve 14 is arranged on each bolt intermediate the web or flange 6 and the adjacent hanger arm 10, to outwardly space the rail end from the latter.

A nut 15 is engaged upon the free end of each bolt 13 beyond the hanger arm, and screwed home to securely bind the parts in desired and proper interconnected relation.

It is sometimes advisable to support the

5 rail 5 from the stiles or sides of the window or door frame, in which case a modified form of supporting means is employed. This modified form of supporting means is shown in Fig. 3 of the drawings, and comprises a horizontal bracket arm 16 provided at its inner end with a stop-shoulder 17 beyond which projects a screw-threaded shank 18 to screw into the stile or side 19 of the window or door frame. A connecting bolt or screw 20 is passed through the web or flange 6 of the rail, so as to screw into the outer end of said bracket arm 16, thus securely fastening the rail end in supported relation to the latter; all of which will be understood from an inspection of Fig. 3 of the drawings.

10 The novel traveling suspension devices which are engaged with and ride upon the rail 5, each comprise a substantially semi-circular yoke or loop 21 adapted to transversely straddle the rail from the under side. The upper free ends of said yoke or loop 21 terminate in inwardly directed arms 22 15 from which extend journal portions 23 of reduced diameter. Mounted upon each journal portion 23 is a rotatable traction ball 24. As will be apparent from an inspection of the drawings, one traction ball 24, at one 20 side of said yoke or loop rides or travels in the track channel 8 of a track flange 7 at one side of the web or flange 6, while the other traction ball 24, at the other side of said yoke or loop rides or travels in the track 25 channel 8 of the other track flange 7 at the opposite side of said web or flange 6, thus providing a two-point ball-bearing traction and traveling suspension means, which will readily move back and forth on the rail 30 in a substantially frictionless manner, and without danger of binding or checking during its travel in either direction.

35 It will be understood that a plurality of the suspension devices, of the kind above described, are employed, to which the curtain or other drapery may be connected, and by which the same may be supported for easy adjustment to either draw the same to closed or open position relative to a window or door 40 frame. The curtain or other drapery may be provided with rings 25 which are suspended upon the yokes or loops 21, or the curtain or other drapery may be fastened directly to the latter in any other manner which 45 may be found convenient or desirable.

45 I am aware that some changes may be made in the several arrangements and combinations of the parts of my novel curtain or drapery suspension means, as well as in 50 the details of the construction of the same, without departing from the scope of this invention as above described, and as defined in the appended claim. Hence, I do not limit my invention to the exact arrangements and combinations of the said parts as hereinabove

described, nor do I confine myself to the exact details of the construction of said parts as illustrated in the accompanying drawings.

I claim:—

5 In a device of the kind described, a rail comprising a medial vertical flange and horizontal oppositely projecting track flanges at the lower end of said vertical flange, each track flange having a concave track channel on its upper side, said rail having curved end-portions extending at substantially right angles to the main body thereof, supporting means for said rail connected with the vertical flange thereof at said curved end-portions, and a traveling suspension device 10 comprising a yoke having inwardly directed free ends terminating in journal portions of reduced diameter extending respectively transversely above the respective track flanges, and traction balls rotatably mounted on said journal portions, said concave track channels conforming to said traction balls so as to prevent lateral play of said yoke while nevertheless permitting free travel thereof on said rail.

15 In testimony, that I claim the invention set forth above I have hereunto set my hand this 9th day of April, 1924.

REUBEN BIGLAND.
